(Cl. D44—10)

To all whom it may concern:

Be it known that I, Eva S. Zeisel, a citizen of the United States and resident of the city of New York, county of New York, and State of New York, have invented a new, original, and ornamental Design for a Hot-Water Plate, of which the following is the specification, reference being had to the accompanying drawings, forming part thereof.

Figure 1 is a side elevation of a hot-water plate showing my new design;

Figure 2, a top plan view;

Figure 3, an end elevation;

Figure 4, a vertical section on the line 4—4 of Figure 2;

Figure 5, a vertical section on the line 5—5 of Figure 2.

I claim:

The ornamental design for a hot-water plate, substantially as shown.

EVA S. ZEISEL.
